CLAIM

The ornamental design for a tennis ball bottle, as shown and described.

DESCRIPTION

FIG. 1 is a perspective view of a tennis ball bottle showing my new design.

FIG. 2 is a left side view thereof, wherein the right side view is a mirror image.

FIG. 3 is a front view thereof.

FIG. 4 is a back view thereof.

FIG. 5 is a top view thereof; and,

FIG. 6 is a bottom view thereof.

The broken lines shown in the drawings depict portions of the tennis ball bottle that form no part of the claimed design.
